UNITED STATES PATENT OFFICE.

ALBERT R. HAAG, OF PEORIA, ILLINOIS.

WASHING MACHINE.

Application filed July 25, 1924. Serial No. 723,079.

To all whom it may concern:

Be it known that ALBERT R. HAAG, a citizen of the United States of America, residing at Peoria, in the county of Peoria and State of Illinois, has invented certain new and useful Improvements in Washing Machines, of which the following is a specification.

My invention relates to washing machines. 10 The invention has special reference to agitating means, its form, and relationing of the same to a container or tub; also the invention has special reference to gear actuating means for agitating member and to 15 matters of details of structure and combinations of parts functioning in obtaining the improved result herein sought to be obtained.

One object of my invention is to provide an agitator seated at the bottom of the receptacle and submerged within the liquid within the container, also the relationing of the agitator member to a support at the bottom of the container in a manner to prevent foreign matter as dirt, or ravelings 25 from the clothes, buttons and the like from entering between agitator and its support; also, the provision in conjunction with or attached to the agitator member, of a baffle member disposed axially with reference to 30 the center of the container and extended upwardly above the position of the normal water line therein and expanded to substantial proportions that it may occupy a substantial portion of the central part of 35 the container, to the end, that, clothing being acted upon within the container will be prevented from centering at the axial or central portion of the container whereby such clothing will be maintained within the zone of 40 largest agitation.

Another object of the invention is the provision of simple inexpensive means for driving the agitator and particularly to a manner of relating a driven member of the 45 driving means to the agitator for driving it from a connection above the normal water line and to associated means effective to prevent any possibility of leakage from the container through the entry point of the 50 driving means through the bottom of the container.

The invention also includes details with 55 reference to the agitator driving means and to special means provided for making or breaking driving connection with the agitator member and to means for locking the

driving means either into or out of operating connection with said agitator means.

The invention also includes the matter of interposing a special journal in association with the driving means for the agitator means to minimize requirement for lubrication.

Referring to the drawings:

Fig. 1, is a plan view of the device with 65 the lid portion broken away and disclosing in dotted lines the arrangement of operating gear parts and driving means below the bottom of a container or tub, also partially in transverse section to show operating 70 means for effecting relative connection or disengagement of driving connection for an agitator member.

Fig. 2, is a side elevation showing a container and parts connected therewith, said 75 container being broken away to show interior operating parts and interior operating parts being partially in section to better illustrate structure and arrangement of 80 parts.

Fig. 3, is a detailed plan view showing an operating means for effecting engagement or disengagement of the gear parts.

Fig. 4 is a side elevation showing the same subject matter as we disclosed in Fig. 3, 85 a portion in said figure being broken away in order to show detailed parts.

Fig. 5, is a vertical sectional view of the upper end of the baffle member associated with the agitator member, as disclosed in 90 Fig. 2, and illustrates the manner of establishing a driving connection with said agitator through said baffle member.

Fig. 6, is a cross sectional view on the line 95 5—5 of Fig. 5.

Referring to the drawings,

10, refers generally to a circular container or tub, 13, are leg supports for the container and 14, is a removable lid or cover.

Referring now particularly to devices 100 featuring in connection with my invention 15, refers generally to a unit structure comprising an agitator and a baffle. Referring to details with respect to this unit structure, 16, is a circular base member provided with 105 depending flanges 17. 18, are agitator members, integral with or attached to base member 17, there being preferably provided four of such members arranged relatively in substantial equal spaced relation. 19, is an 110 up-standing baffle member of substantial diameter, extending upwardly to a point above

the normal water line of the container, the upper portion of said baffle being extended as at 20, and interiorly vertically perforated to provide an angular space as at 21^a, the 5 same being slightly tapered as shown, (see Figs. 1 and 5), to provide a seat for a driving member hereinafter referred to.

A circular seat 22, for the agitator member is fixed to the central portion of the bottom 10 of the container and is relatively proportioned to such agitator that when the agitator member is seated upon the support, the flange member 17, of the former will overlie the periphery of such seat and in 15 such fitted relation, that, relative reciprocation will be permitted and at the same time shall be so close a fit that foreign matter will not be permitted to enter between the joint thus established.

20 It will also be appreciated that the member 22 will also serve to center the agitator and prevent undesirable lateral movement which would otherwise have a tendency to take place owing to the distance at which 25 the agitator is supported above the point where the greatest thrust action occurs. While the lateral movement referred to is effectively prevented by the member 22, it will be apparent that such movement may 30 be prevented by various other arrangements provided for this particular purpose, and the applicant does not wish to be limited to the specific centering means disclosed.

To safeguard against leakage through 35 the entry into the container of driving means for the agitator member, a sleeve 23 is provided, the same having such close threaded connection with agitator supporting member 22 as to prevent leakage, said 40 sleeve extending upward to a point above the normal water line of the container, its upper end serving as a seat for a special journal hereinafter referred to.

24, is a ring member attached at the bottom 45 portion of the container and serves as a support for gear housings and various operating mechanisms including a motor and gear parts, however, as such supports and gear housings form no part of the present invention, no detailed disclosure or 50 special reference is made thereto.

Referring now particularly to operating means for the agitator, 25, is a vertical shaft having journaled bearing in sleeve member 26, depending from ring member 24, and also in sleeve member 27, depending from gear casing member 28, forming a part of and depending from ring member 24, there 55 being fixed to said shaft, gear wheel 29, provided with a hub portion 30, said hub 60 and gear being dimensioned with respect to sleeve member 26 and the bottom of housing 28 to permit it to be reciprocated. The upper end of shaft 25 (see Fig. 5) is mutilated to form a flat face thereon, and to

it is attached a clutch member 31, having a central opening fashioned in conformity to the upper end of shaft 25, and is secured thereto by means of pin 32, said clutch member being fashioned with angular outer faces 70 to adapt it for entry and co-operation with the similar tapered angular opening 21^a in the extension portion 20 of baffle member, said clutch member also being provided with an annular flange 33 at its lower end 75 adapted to engage offset portions at the lower extremity of extension 20, thereby forming a stop to facilitate proper relationing of said clutch to its seat within extension 20. In practice, member 15, comprising 80 the agitator and baffle member is so proportioned with respect to seat 22^a and clutch member 31, that, when said agitator is placed in proper working position upon its support, the supporting tension for said 85 agitator will be divided between supporting member 22, and flange member 33.

It will be noted that the unit structure 15, comprising the agitator and baffle member, may be readily removed from its seat 90 and driving connection by simple vertical lift, without the requirement for release of parts or mechanisms.

A special journal bearing is provided for the upper end of shaft 25, to meet the circumstances of its being located in a position where ordinary oiling is not feasible, due to the danger of leakage to the container. The bearing is indicated at 34, and is 95 formed from a porous substance, as wood, to 100 facilitate its being saturated with oil. A bearing of ready oil absorbing quality, either of wood or other serviceable material, having been saturated with oil and sleeved within the upper end of tubular member 23, 105 forms a bearing that requires infrequent resaturation and is so related to the mechanism that it may be readily removed for saturation or to facilitate substitution of another similar journal. 110

With reference to the driving connection for reciprocating the agitator, 35, is a gear segment swingably in connection with swinging arm 36, the latter being longitudinally adjustably pivoted in conjunction 115 with a cam member, hereinafter referred to. Gear segment 35, is caused to be reciprocated through a definite distance through and by means of a bar member 37, driven from a crank arm 38, fixed to driven shaft 39, said 120 shaft being suitably supported in connection with gear housing 40, the latter being suitably connected with a general framing. Shaft 39, is driven through worm wheel 41, fixed thereon, the latter being driven 125 from worm 42, on shaft 43, said shaft 43, being driven from belt wheel 44, which said belt wheel is in turn driven from a wheel and belt connection with motor 46.

A driving connection is shown to a 130

wringer operating shaft, however, as this feature is not included in the present invention, said driving connection for the wringer is not herein specially referred to.

5 In the operation of the agitating member within the container, it is necessary that means be provided for effecting disconnection with the driving means for such agitating means without stopping the motor and 10 to that end I have provided the cam member 47, co-operatively seated in connection with swinging arm 36, to which segment gear 35, is attached, whereby upon the turning of said eccentric member within its seat 15 in arm member 36, the latter will be caused to be retracted or extended to effect optional engagement or disengagement of segment gear 35, with gear member 28, on agitator shaft 25, thereby provided for engagement 20 or disengagement of the driving connection to the agitator. The particular means for operating cam member 47, include vertical shaft 48, (to which said cam is fixed), journaled in bracket member 49, at the bottom 25 portion of the container and its upper end journaled in boxing member 50, said boxing member being provided with an outwardly extending flange 51, provided with locking seats 52 on the underface thereof. A rocker 30 arm 53, is fixed to shaft 48, and is provided with a spring seat 54, within which spring 55, is carried. 56, is a ball so disposed with respect to spring 55, and the lower face of flange 51, that the same will be permanently 35 held between said spring and flange members and as the rocker arm 53, is turned, the ball may be caused to register optionally with either of the seats 52, thereby affording locking means to hold the gear segment 40 35 either into or out of engagement with gear member 29.

What I claim is:

1. In a washing machine, in combination, a clothes container, an agitator therein, a member extending upwardly from the agitator member to a point above the normal water level therein fashioned at its upper end to provide a driving connection for agitator operating means, a driving member 45 for said agitator extending upwardly through the bottom of the container and fashioned at its upper end for detachable driving connection with the extension from the agitator member, means for reciprocating the agitator driving member, and a supporting and guard element interposed between the agitator and the bottom of the tub to prevent the entrance of extraneous matter beneath the agitator.
2. In a washing machine, in combination, a tub or container, an agitator member, a member extending upwardly therefrom fashioned at its upper end to provide a driving connection for driven member, a suitably supported driven member extending 50 55 60 65 70 75 80 85 90 95 100 105 110 115 120 125 130 upwardly through the bottom of the container and through the extension member of the agitator fashioned at its upper end for driving engagement with said agitator extension, a guard element interposed between the agitator member and the bottom of the tub, and means for reciprocally driving said driven member, a sleeve member projecting upwardly from the guard element to a point above the normal water line and surrounding the driven member.
3. A washing machine, in combination, a container, an agitator member, means interposed between the agitator and the bottom of the container for supporting said agitator member and excluding extraneous matter from entering between said member and the bottom of the tub, a circular baffle member of substantial diameter extending upwardly from the agitator to a point above the normal water line fashioned for driving connection with the driven member of the drive shaft, a suitably supported driving shaft extending upwardly through the bottom of the container to a point to accommodate driving connection with the upper end of the baffle member, means for reciprocating the drive shaft and a sleeve member connected with the bottom portion of the container and extending upwardly therefrom to a point above the normal water line, serving as a housing for the drive shaft.
4. In a washing machine, in combination, a container, a circular seat disposed about the axial center of the container and extending upwardly from the bottom thereof, a disc member similarly circularly fashioned and having a downwardly extending peripheral flange adapted to overlie the circular seat, a circularly fashioned baffle member extending upwardly from said disc to a point above its normal water line and disposed about a line through the axial center of the disc and fashioned at its upper end in a manner to effect driving connection with a drive shaft, a plurality of agitator members disposed radially on said disc and intervening between the baffle wall and the outer end of said disc, a suitably supported drive shaft extending upwardly through the bottom of the container to a point of the normal water line therein, fashioned at its upper end for driving connection with the baffle member, means for reciprocating the drive shaft to effect reciprocation of the baffle and associated disc, a water seal including a tubular member housing said drive shaft connected with the disc seat at the bottom of the container and extending upwardly to a point above the normal water line within the container, a bearing for the upper end of the drive shaft supported in connection with the sleeve member of the seal.
5. A washing machine having in combina-

- tion a container, an agitator within said container, a member interposed between said agitator and the bottom of the container, the said member being adapted to prevent the entrance of water and dirt beneath the agitator, and means for reciprocating the agitator upon said member.
6. In a washing machine, in combination, a container, an agitator disc, a support for said disc including a relationing of the support and disc to effect an overlying of a portion of the latter over the former to provide a seal against the admission of foreign substances between said agitator and support, a baffle member connected with and extending upwardly from the disc to a point above the normal water line of the container, agitator members on the agitator disc, a drive shaft extending upwardly within the container for engagement with the baffle member to reciprocate the same in conjunction with said agitator disc and means for reciprocating said shaft to effect reciprocal activity of the agitator disc and a water seal housing said shaft connected with the shaft entry way to the container and extending upwardly to a point above the normal water line of the container.
7. A washing machine having in combination, a container, an agitator disk within said container, a stationary disk interposed between the agitator and the bottom of the container forming a substantially watertight connection between the agitator and the bottom of the container, a baffle member connected with the central portion of the agitator disk and extending upwardly to a point above the normal water line of the container, a drive shaft for said agitator having a driving connection with the baffle member at a point above the normal water line, a tubular member connected to said disk and interposed between said drive shaft and the baffle member, and means for reciprocating said shaft.
8. A washing machine having in combination a container, an agitator within said container, and a baffle member at the central portion of the bottom of the container, said baffle member being adapted to prevent the entrance of water and dirt beneath the agitator and to center the agitator, and means for reciprocating the agitator.
9. A washing machine having in combination a container, an agitator within said container and a baffle member at the central portion of the bottom of the container directly inter-related with the agitator and the bottom of the container to prevent the lateral movement of the agitator, and means for reciprocating the agitator.
10. A washing machine having in combination a tub, a driving member projecting through the bottom of the tub to a point above the normal water line thereof, an agitator adjacent the bottom of the tub, means for supporting the agitator from the upper extremity of the driving member, and means directly associated with the agitator and the bottom of the tub to prevent lateral movement of the agitator.
11. A washing machine having in combination a container, an agitator within the container and adjacent the bottom thereof, means for reciprocating the agitator and means interposed between said agitator and the bottom of the container to center the agitator and prevent lateral movement thereof.
12. A washing machine having in combination, a tub, a driven member extending upwardly therein to a point above the normal water line, an agitator actuated by said driven member and, detachable therefrom by a vertical lift, said agitator comprising a main laterally extending body portion disposed adjacent the bottom of the tub, and a sleeve member extending upwardly from the main body portion to a point above the normal water line of the tub, the upper end of said sleeve being driven and centered by said driving member and a member engaging said laterally extending body portion for centering the lower portion of the agitator against lateral movement.
13. A washing machine having in combination a tub, provided with a central opening in the bottom thereof, a tubular member within the tub in axial alignment with said opening, the said tubular member projecting upwardly to a point above the normal water line of said tub, a driving member projecting through the opening in the bottom of the tub and the tubular member to a point beyond the upper end of said member, an agitator located adjacent the bottom of the tub, a sleeve member connected to the agitator and spaced from the tubular member, means for connecting the upper end of the sleeve member to the upper end of the driving member, and guarding and centering means directly associated with the said agitator adapted to prevent lateral movement of the agitator and exclude the entrance of foreign matter thereunder.

In testimony whereof I affix my signature.

ALBERT R. HAAG.
